UNITED STATES PATENT OFFICE.

WILLIAM G. MINER, OF CHATHAM, VIRGINIA.

DOOR FOR AUTOMOBILES.

1,087,809.

Specification of Letters Patent.

Patented Feb. 17, 1914.

Application filed December 4, 1911. Serial No. 663,947.

To all whom it may concern:

Be it known that I, WILLIAM G. MINER, a citizen of the United States, and a resident of Chatham, in the county of Pennsylvania and State of Virginia, have invented an Improvement in Doors for Automobiles, of which the following is a specification.

Doors of automobiles are ordinarily arranged to swing outward, which is objectionable for several reasons.

I have devised an improvement by which doors are adapted to slide horizontally in guideways and pockets provided in the body of the vehicle, and I have provided such doors with spring attachments as a means or aid for closing them.

My invention is hereinafter described in detail and illustrated in the accompanying drawing in which—

20 Figure 1 is a side view of an automobile body provided with horizontally sliding doors and attachments thereof according to my invention. Fig. 2 is a horizontal section on the line 3—3 of Fig. 1. Fig. 3 is a vertical section on the line 5—5 of Fig. 2.

The automobile body 1 is shown provided with two doorways, each having a rigid slidable door 2 for closing them. The rear door is shown closed and the other open. 30 The doors are adapted to slide in pockets or chambers 3 formed in the body 1, as will be understood by reference to Figs. 2 and 3, and guides 4 are provided at top and bottom, as indicated in Fig. 3. The doors are 35 provided with a spring attachment for automatically closing them and which also serves to hold them normally closed, or aiding in closing them. A rod 5—see Figs. 2 and 3—is arranged horizontally and centrally in

the pocket 3 and its ends are bent inward 40 and secured to the inner wall of the pocket. A door 2 is adapted to slide alongside this rod, and a spiral spring 6 operatively connects them; that is to say, one end of the spring is coiled about the inner or rear end 45 of the rod 5 and the other end is attached to the inner end of the door 2. In Fig. 2, this spring is shown by full lines compressed, and by dotted lines as expanded. In other words, the normal contraction of the spring 50 draws, or tends to draw, the door back into the pocket, and, when the door is drawn out and thereby closed, the spring is expanded the whole length of the rod 5. It will be noted that the spring is coiled about the inner portion of the rod which, as shown in Fig. 2, projects beyond the door when the latter is fully open. It will be noted that the arrangement of the rods 5 horizontally 55 in the vertical middle of the pocket prevents 60 the door binding at top and bottom, so that it slides easily in either direction.

What I claim is:—

An automobile body having a side pocket and a door which is slidable therein, a rod 65 fixed horizontally within the pocket parallel to the door, the same extending from the outer end of the pocket inward beyond the door when the latter is fully open, and a spiral spring coiled on such inner extended 70 portion of the rod, its ends being connected with the door and rod respectively, as described.

WM. G. MINER.
